UNITED STATES PATENT OFFICE.

JAMES N. MAYHEW, OF MINNEAPOLIS, MINNESOTA.

DESIGN FOR A SHOE-HORN.

58,797.

Specification for Design.

Patented Aug. 30, 1921.

Application filed December 27, 1920. Serial No. 433,491. Term of patent 14 years.

To all whom it may concern:

Be it known that I, JAMES N. MAYHEW, a citizen of the United States, residing at Minneapolis, in the county of Hennepin and State of Minnesota, have invented a new, original, and ornamental Design for Shoe-Horns, of which the following is a specification, reference being had to the accompanying drawing, forming part thereof.

The figure is a perspective view of a shoe horn showing my new design.

I claim:

The ornamental design for a shoe horn, as shown.

JAMES N. MAYHEW.
